UNITED STATES PATENT OFFICE.

RICHARD E. BABCOCK, OF BARCROFT, VIRGINIA, ASSIGNOR, BY MESNE ASSIGNMENTS,
TO CASSIUS S. CHASE, OF HARTFORD, CONNECTICUT.

FASTENING MEANS.

1,279,217.

Specification of Letters Patent. Patented Sept. 17, 1918.

Application filed February 20, 1918. Serial No. 218,262.

To all whom it may concern:

Be it known that I, RICHARD E. BABCOCK, a citizen of the United States, residing at Barcroft, in the county of Alexandria and 5 State of Virginia, have invented certain new and useful Improvements in Fastening Means, of which the following is a specification.

This invention relates to fastening means 10 or connecting devices, and resides especially in the means for readily fastening or anchoring the links of a chain or part or parts of some element or elements, and in provision for locking said means in normal position.

The invention hereinafter set forth and described is intended primarily for use in attaching anti-skidding chains, of the fixed point or anchored type, to the felly or other 20 part of an automobile truck wheel. However, the invention may be embodied in a number of forms to be fixed in position in various manners and, while primarily intended for use with anti-skidding devices, 25 as above mentioned, it can be used equally well for a great variety of purposes.

The primary object of the present invention is to provide a plate with a pivotally mounted bar having oppositely disposed 30 arms at ends, which arms are adapted to receive ordinary twisted chain links and have their ends received in recesses in said plate when said bar is in normal position.

A further object is to provide means for 35 releasing said bar and for locking it in normal position, the arrangement and construction of the parts being so calculated as to throw the minimum amount of strain on said means when all parts are in normal 40 position with an anti-skidding, or other, chain or chains applied to the arms.

A further object is to provide sufficient clearance between the arms and the plate to allow the chain links, or other elements, 45 to be slipped over the ends of the arms.

A further object is to so form the bar, plate and releasing and locking means that the three elements will constitute a self-contained unit, no part of which can become 50 separated, by manipulation by hand or with any ordinary tool, and so become lost. Quite commonly persons operating trucks are not mechanically inclined and might separate the parts without need and then lose one or 55 more of the parts. With this fact in view

it is desirable to so form the parts that after being assembled and finished they are difficult to separate.

In the accompanying drawings, in which only the preferred form is illustrated; 60

Fig. 1 represents a perspective view of a device embodying the invention;

Fig. 2, a plan view thereof;

Fig. 3, a cross sectional view on the line 3-3 of Fig. 2; and 65

Fig. 4, a cross sectional view on the line 4-4 of Fig. 2, looking in the direction of the arrows.

Referring now in detail to the drawings, A indicates the plate having at each end 70 and on opposite sides a perforated lug B through which any suitable fastening device, such as a bolt or lag-screw, not shown, may be passed to fasten the plate to the felly of a truck wheel or to any other relatively 75 fixed object.

This plate A is provided at each end and on opposite sides with a preferably recessed lug preferably formed integral with the plate, each lug extending preferably about 80 three-fourths of the length of the plate and toward the other end thereof.

1 designates one of these lugs, which is preferably plain and solid, except for its recess 3 and 2 designates the other of said 85 lugs, which is also preferably plain except for its recess 3 and a slot 4 extending through said lug and transversely thereof.

The portion of said plate between said lugs 1 and 2 is provided with a preferably 90 integral raised oblong portion or shoulder 5 and is provided at its central point with a perforation through which passes a pivot pin 6.

A spacing collar 7 is slipped over the upper end of pin 6, the bar 8 is then slipped over the upper end of said pin and the ends of the pin are then upset or spread, as clearly shown in Fig. 3, leaving, however, sufficient play to permit the turning or pivoting of the bar 8 thereon.

A releasing and locking bolt 9 is inserted in the slot 4 and has its inner end bifurcated to receive between the bifurcations 10 thereof a portion of the bar 8, which portion of 105 said bar and the bifurcations 10 are perforated to receive a pivot pin 11, the ends of which are upset or spread for obvious reasons.

The outer portion of this bolt 8 is screw- 110

threaded to receive a wing-nut 12, which is preferably round and of sufficient size to generously span the slot 4. After the nut has been screwed on the outer portion of bolt 5 8 the extreme outer end thereof will be preferably upset or spread as at 13 to prevent the separation of the nut 12 therefrom.

The bar 8 above referred to is provided on each end with an arm 14, said arms being 10 disposed in reverse directions and having their outer ends received, in normal position, in the respective deep recesses 3 in the respective lugs 1 and 2. The opposing faces of said arms are each provided with a recess 15 15, the deepest point of which lies on the central longitudinal line of said plate A, which line also passes through the axis of pin 6, so that the terminal links C of the chain or chains or other element or elements 20 will engage the arms at this point and pull in diametrically opposite directions, throwing practically all the strain on the arms 14, bar 8 and plate A and putting practically no strain on the pin 6 and the bolt 9 with its 25 bifurcations 10 and the pin 11.

In operation, to apply the chain links C or other elements to be connected, fastened or anchored, the nut 12 will be unscrewed sufficiently to allow the bar 8 to be turned 30 on pin 6 until the ends of arms 14 lie on the longitudinal central line of plate A, when the links C may be slipped over the ends of said arms 14. The nut 8 will then be screwed up on the bolt 9 until the ends of 35 said arms 14 are held firmly against the inner walls of the recesses 3. To remove the links C the same operation is repeated, except that the links C are withdrawn from the arms instead of being applied thereto, 40 and the only reason for tightening the nut 8 then will be to prevent rattling.

The slot 4 is of course, of sufficient dimensions to allow the inner end of the bolt 9 to describe an arc of sufficient magnitude to allow the ends of arms 14 to lie on the longitudinal central line of plate A, with pin 6 as 45 the center of such arc.

It is obvious, of course, that in case the arms 14 or bar 8 should become stuck in 50 normal position, by ice or other foreign matter, it may be quickly freed by tapping the free end of the bolt 9.

The bar 8 with its arms 14 will preferably be of drop-forged steel, though any 55 suitable material may be used for this part as well as any other parts of the device.

Having thus described my invention, what

I claim as new and desire to secure by Letters Patent is:

1. A plate provided with a recessed lug 60 on each end and on opposite sides, in combination with a pivotally mounted bar having oppositely disposed arms, the ends of which are located in said recesses when said bar is in normal position, and means for 65 locking said bar in normal position.

2. A plate provided with a recessed lug on each end and on opposite sides, in combination with a pivotally mounted bar having oppositely disposed arms, the ends of which 70 are located in said recesses when said bar is in normal position, and means for locking said bar in normal position, the opposing faces of the upset arms being recessed, the deepest part of each recess lying on a line 75 cutting the axis of the pivot of said bar.

3. A plate provided with a recessed lug on each end and on opposite sides, in combination with a pivotally mounted bar having oppositely disposed arms, the ends of which 80 are located in said recesses when said bar is in normal position, a bolt pivotally connected to said bar and extending through one of said lugs and a nut working on said bolt and adapted to engage the external face of said 85 lug to hold said bar in normal position, the extreme free end of said bolt being spread to prevent removal of said nut therefrom.

4. A plate provided with a recessed lug on each end and on opposite sides and having 90 between said lugs a raised perforated shoulder, in combination with a bar pivotally mounted on a pin passing through said perforation and provided with oppositely disposed arms having their ends received in 95 said recesses when said bar is in normal position and means for holding said bar in normal position.

5. A plate provided with a plurality of recessed lugs, a bar mounted for movement 100 on said plate and having arms the respective ends of which are adapted to be received by the respective recessed lugs when said bar is in normal position, and means for locking said bar in normal position, each of said 105 arms being adapted to receive an endless article when out of normal position.

In testimony whereof, I have signed my name to this specification in the presence of two subscribing witnesses,

RICHARD E BABCOCK.
